(57) **CLAIM**

The ornamental design for a vehicle collision safety device, as shown and described.

DESCRIPTION

FIG. 1 is a side perspective view of the vehicle collision safety device in functioning position;

FIG. 2 is a front view thereof;

FIG. 3 is a back view thereof;

FIG. 4 is a left view thereof;

FIG. 5 is a right view thereof;

FIG. 6 is a top view thereof;

FIG. 7 is a bottom view thereof;

FIG. 8 is a perspective view of the vehicle collision safety device in resting position on a vehicle;

FIG. 9 is a perspective view of the vehicle collision safety device in functioning position on a vehicle; and

FIG. 10 is a side view thereof.

The broken lines of FIGS. 8-10 illustrate environment that forms no part of the claimed design.
